UNITED STATES PATENT OFFICE.

HARRY B. GOULD, JR., OF HARTFORD, CONNECTICUT, ASSIGNOR TO THE MERROW MACHINE COMPANY, OF HARTFORD, CONNECTICUT, A CORPORATION OF CONNECTICUT.

SEWING-MACHINE.

1,319,277.

Specification of Letters Patent.

Patented Oct. 21, 1919.

Application filed June 13, 1917. Serial No. 174,597.

To all whom it may concern:

Be it known that I, HARRY B. GOULD, Jr., a citizen of the United States, residing in the city of Hartford, county of Hartford, 5 State of Connecticut, have invented certain new and useful Improvements in Sewing-Machines; and I do declare the following to be a full, clear, and exact description of the same, reference being had to the accompanying drawings, forming a part of this specification, and to the characters of reference marked thereon.

This invention relates to sewing machines for producing ornamental stitching upon fabric edges. Such stitching is much used in finishing underwear, and in a particular form as produced by a Merrow crocheting machine, is commonly known as the shell stitch. This form of finish is characterized 15 by stitches secured in groups to the fabric near the edge at points comparatively widely separated. Each group of stitches comprises upper and lower loops radiating from their common point of fabric penetration 20 to beyond the edge of the fabric where they are enchain'd to form a continuous scalloped border, the finish simulating in its entirety a row of shells with their sides in contact. Obviously the scalloped effect is 25 due to the fact that the radial stitches or loops mentioned are usually of substantially uniform length or, in other words, they are radii of an arc assumed by the concatenated border. It also follows that that 30 part of the border which is midway between the apexes of the scallops or shells is nearest to the edge of the fabric. I find that by securing these mid-portions to the fabric by stitches with radii considerably shorter than 35 those forming the radii of the shells, a very firm ornamental finish with an accentuated scalloped appearance is produced.

The object of the present invention is the provision in a shell stitch machine of means 40 for producing a shell stitch finish with the concatenated border of the shells secured to the fabric by stitches intermediate the points from which stitches forming the shells radiate.

50 Salient features of the means employed include feed mechanism alternately effective at intervals of different duration, a movable stitch finger having parts of different width about which different stitches of a

finish are respectively formed, suitable take-ups and automatic tension devices operable in correlation to movements of the feed mechanism and stitch finger all of which will be fully set forth in the following description of the accompanying drawings 60 wherein one form of embodiment of my invention is illustrated.

In the drawings,

Fig. 1, is a front elevation of a Merrow shell stitch machine provided with mechanism comprising my invention.

Fig. 2, is an enlarged diagrammatic detail view of an edge finish formed in accordance with my invention.

Fig. 3, is a plan view of part of the front 70 end of the machine shown in Fig. 1 with the work plate broken away to disclose the feed mechanism, and—

Fig. 4, is an end elevation of the feed mechanism shown in Fig. 3.

Like characters of reference designate similar parts throughout the several views of the drawings which it will be noted are not all of the same scale.

Referring to the drawings, the stitch-forming elements comprise the needle 1, crochet hook 2, chaining finger 3 and supplemental thread carrier 4. The needle is mounted in a bar 5, for reciprocation in a path extending through the needle plate or 80 work plate, adjacent the forward end of the chaining finger, and is driven from the main shaft 8, through intermediate elements as eccentric 9, connecting rod 10, lever 11, link 12, and needle bar clamp 13. The crochet 90 hook 2, held in carrier 14, is adapted to reciprocate in a path extending above and below the needle plate, and passing around the chaining finger, said carrier 14, being pivoted on a block 15, slidably mounted on 95 the inner face of a frame cap 16, whereby movement of said hook in the defined path may be imparted by a pair of intergeared grooved cam cylinders 17 and 18, which are respectively engaged by oppositely extending arms 19 and 20, of carrier 14. Cam cylinder 17, rotates with the main shaft of the machine, to which it is secured, and through gears 22 and 23, effects simultaneous rotation of cam cylinder 18, which is 100 mounted on shaft 24, as will be clearly understood.

The supplemental thread carrier 4, is

secured in a rock shaft 25, suitably mounted on the machine frame and provided with an arm 26, adapted to engage cam 27, rotative with cam cylinder 18. Arm 26 is yieldably held against cam 27, by a spring as 28, coiled about the rock shaft 25, whereby rotation of said cam effects an oscillatory movement of carrier 4, which causes the free end of said carrier to move across the path of the needle. This supplemental thread carrier is not essential to effect the formation of stitches but is preferably employed to introduce into the stitches an additional thread to enhance the beauty of finish and produce 10 a more substantial edge.

A fabric edge guide as 30 is adjustably attached to the frame cap and serves the usual purpose of such devices to regulate the depth of stitch.

Work engaging feed elements comprise 20 the presser foot 34, and feed dog 35. To permit of the required reciprocation of the feed dog it is associated with a slide 36, and in order that movement of the feed dog 25 with respect to the work may be rendered effective or ineffective to advance the work, the slide is mounted in a shiftable member such as a guide bar 37, fulcrumed at one end on a stud 38. Obviously the position 30 of guide bar 37, determines the position of the feed dog with respect to the work plate 6, and therefore the relation of the feed dog to the work supported by the work plate. Slide 36, which is fitted in a groove 40, of 35 the guide bar, and laterally supported by a contiguous wall 41, of the machine frame, is free to be reciprocated longitudinally of the guide bar by mechanism indicated in a general way by 42. This mechanism includes 40 a rock lever 43, connected by a link 44, with an eccentric 45, on the main shaft 8. At one end, rock lever 43, is fulcrumed on a short shaft 46, and at its other end it is provided with a slot 47, adapted to receive a pin 48, projecting rigidly from slide 45 36, through a slot 49, in guide bar 37. Intermediate its ends, rock lever 43, is provided with an elongated slot 50 wherein a stud 51, connecting said lever and link 44, 50 may be adjusted to vary the amount of throw imparted to the rock lever, thus regulating the reciprocatory movement of slide 36, and the feed dog 35, relative to the guide bar. From the foregoing description it will 55 be apparent that when the machine is in operation the feed dog is continuously reciprocated. In other words, a complete reciprocation of the feed dog occurs for each cycle of the stitch forming elements. The 60 feed dog, however, is effective for advancing the work only when the guide bar 37 is shifted to the position in which it is shown in Fig. 4, during intervals when said feed dog is moving in the direction of arrow "A". 65 If the guide bar were thus shifted for each

stitch forming cycle, the work would be correspondingly advanced step by step, and the needle would make a separate penetration for each stitch. If, however, the shifting of the guide bar is effected only at intervals of several stitch forming cycles, no advance in the work will be effected except at the completion of such intervals, and consequently a corresponding number of stitches will be secured at practically one point of 70 needle penetration, and if, for example, the non-feeding interval extends over eight stitch-forming cycles, a cluster or shell of 75 eight stitches will be produced. The style of finish diagrammatically illustrated in 80 Fig. 4, consists of eight stitch shells with their concatenated border, at adjacent points of consecutive shells, secured by a single stitch penetrating the fabric at a point about midway between needle penetrations, 85 at which are secured the radial stitches of respective shells.

To produce this finish the required action of the feed mechanism consists in advancing the work step by step of uniform length 90 at intervals alternately of eight stitch cycles and a one stitch cycle.

Mechanism for correspondingly shifting the guide bar 37, is indicated in a general way by 56. It includes a gear 58, mounted 95 on a stud 59, and meshing with a pinion 60, at the extreme end of main shaft 8. Secured to the gear 58, is a cam 61, having two rises 62 and 63, adapted, upon rotation of the gear, to alternately actuate the guide 100 bar 37, through interposed parts comprising the shoe 64, fitted to the guide bar, and a pin 65, carried by an arm 66, pivoted at 67. The guide bar shoe is provided with a side flange 68, having an elongated slot 105 69, to receive the attaching screw 70. The surface of shoe 64, with which pin 65 engages, is so disposed that adjustment of the attaching screw along the guide bar will vary the position of the feed dog carried 110 by the guide bar with respect to the work. When the pin 65, is not engaged by either of the cam rises it is retracted against a stop 72 by the influence of spring 73, housed in a bore of the machine frame and adapted 115 to exert a suitable pressure against that edge of the guide bar which is opposite the said pin 65.

It will be understood that the ratio of pinion 60 to gear 58, and the circumferential 120 intervals between the cam rises 62 and 63, determine the number of stitches that the mechanism is adapted to produce after each advance of the work. As shown the number of teeth in the pinion is to the number 125 of teeth in the gear as one is to nine, *i. e.* for each revolution of the gear there are nine stitch-forming cycles. During these cycles the cam rises 62 and 63 each operate once to raise the feed dog into work ad- 130

vancing position respectively after intervals of eight stitch-forming cycles and one stitch-forming cycle. The result is a grouping of stitches like that shown in Fig. 2.

5 As already set forth the single stitch loops between the shells are much shorter than those composing the shells. The variation involved is controlled by take-ups, mechanism for shifting the chaining finger and 10 devices for changing the tension on the thread, all in a manner that will now be described.

The chaining finger 3, mounted for sliding movement on the work-plate is provided 15 at its inner end with a narrow part 73 and a wider part 74. During the formation of the stitches composing the shells the stitch finger is shifted so that the wide part 74, occupies the field of stitch formation, while 20 during the formation of the shorter or intermediate stitch, the stitch finger is shifted so that its narrow part 73, occupies the field of stitch formation.

Any suitable means may be employed for 25 shifting the stitch finger. As shown they include a rock shaft 75, mounted in bracket 76 secured to the under side of the work-plate. At one end of the rock shaft there is secured an arm 77, connected at its outer 30 end with the stitch finger 4, by a link 78. To the other end of the rock shaft there is clamped an arm 79, extending into engagement with the cam 80, adjustably secured by screws 81 to the gear 58. The arm 79 35 is held in contact with cam 80 by a spring 82, so that when the cam is rotated its effect together with that of the spring causes the arm to oscillate. The motion is transmitted through shaft 75, arm 77, and link 40 78, to the stitch finger so that the narrow part of the latter is positioned for the short stitches and its wide part for the long stitches in accordance with the requirements already described.

45 Thread controlling mechanism for increasing the tension upon the thread during formation of the short intermediate stitches may be of any suitable nature, as shown it includes a cam 90, adjustably secured by screw 91 to cam 80, by virtue of which it will be evident that both cams rotate in unison with the gear. A lateral rise 93 on cam 90 is adapted to intermittently engage an arm 94, clamped to one end of 50 a rod 95, which is held in some suitable manner for endwise movement only. As shown the rod is square for a part of its length and this part is supported so that it cannot rotate in the square hole of a bearing 96. Beyond the bearing 96, the rod is extended through the machine frame at 97, and threaded at its end to receive the bifurcated head 98. Supported on a fulcrum stud 99, projecting from the frame cap 16,

is a lever 100, having one end pivoted to 65 head 98 and the other end slotted to engage a pin 101, carried by a tube 102, sleeved upon the tension supporting stud 103, back of the tension disks 104. Obviously by sliding tube 102, along the tension stud the tension spring is affected in a manner to vary the pressure exerted by the tension disks. Normally, due to effect transmitted through the lever 100, and associated parts, the tube 102 is held against the machine frame as 70 shown in Fig. 1, by the spring 105, which surrounds rod 95 between the machine frame and head 98. This is the position of tube 102, maintained for tensioning the 75 thread while the shell stitches are being 80 formed. Suitable tension for the intermediate stitches, *i. e.* an increased tension, is produced when cam 90, engages arm 94, thereby shifting rod 95 to the left and tube 102 to the right as seen in Fig. 1.

85 Between tension disks 104 and the thread guide 106 the thread may be passed through an eye in pin 101, such an arrangement serving through the described movement imparted to said pin to effect a controlling 90 action upon the thread.

Means for controlling the supplemental thread comprise a tension device 108, and a thread engaging element 109, mounted on lever 11. The tension device being near the 95 fulcrum of lever 11, partakes slightly of the movement of the latter. A more amplified movement is imparted to thread engaging element 109 which oscillates between thread guides 110 and 111, said thread 100 guides being secured to the machine frame. The effect of the combined movements of tension device 108, and thread engaging element 109, causes pulling off and taking up of the thread at suitable intervals and in 105 desired amounts.

The various parts of the machine having been described in detail their mode of operation may be concisely stated as follows:—Assuming the machine to be in motion with the work properly introduced beneath the presser foot to receive stitches, the needle, for eight stitch-forming cycles, penetrates the work at substantially the same point eight times to form eight stitches, 115 with tensions, take-ups and stitch fingers adjusted to produce shells of desired form. The cam rise 62 then causes the feed mechanism to advance the work half the distance to the point where the next shell is to be 120 attached. During the next stitch-forming cycle cam 80, and cam 90, respectively shift the stitch finger and alter the tension on the thread so that a stitch composed of loops much shorter than those of the shells is produced. The stitch altering devices are then caused to resume their relation for producing the loops of the next shell; and after 125

another advance of the work caused by the effect of cam rise 63 on the feed mechanism, the described action repeats.

Having thus described my invention what I claim is:

- 5 1. In a sewing machine in combination with stitch forming elements, work feeding mechanism, operable to effect its work advancing action between consecutive intervals of different numbers of stitch forming cycles, a shiftable stitch finger having parts of different cross sectional area, and means for shifting the stitch finger during the work advancing action to move into the field of stitch formation a different part thereof for each consecutive interval of stitch forming cycles.
- 10 2. In a sewing machine in combination with stitch forming elements, work feeding mechanism operable to effect its work advancing action between consecutive intervals of different numbers of stitch forming cycles, a shiftable stitch finger having parts of different cross sectional area, means for shifting the stitch finger to move into the field of stitch formation a different part thereof for each consecutive interval of stitch forming cycles, and means for differently tensioning the thread for each consecutive interval of stitch forming cycles.
- 15 3. In a sewing machine in combination with stitch forming elements a feed dog, a rotary shaft, mechanism driven by the shaft for reciprocating the feed dog, a pinion rigid with the shaft, a gear in mesh with the pinion, a cam associated with the gear for moving the feed dog into work engaging relation, at consecutively unequal intervals, a shiftable stitch finger having parts of different cross-sectional area, and means operable during the work advancing action for moving a different part of the stitch finger into the field of stitch formation for each consecutive interval between engagements of the feed dog with the work.
- 20 4. In a sewing machine in combination with stitch forming elements, a feed dog, a rotary shaft, mechanism driven by the shaft for reciprocating the feed dog, a pinion rigid with the shaft, a gear in mesh with the pinion, a cam associated with the gear for moving the feed dog into work engaging relation at consecutively unequal intervals, and means also associated with the gear for changing the tension on the thread at each consecutive interval between advancing engagements of the work by the feed dog.
- 25 5. In a sewing machine, in combination with stitch forming elements, mechanism operable between consecutive intervals of different numbers of stitch forming cycles to feed the work, and means for changing the tension upon the thread during advance of the work.
- 30 6. In a sewing machine, in combination

with stitch forming elements, work feeding mechanism for advancing the work at intervals wherein respectively the number of stitch forming cycles executed varies, a stitch finger and means operable during the work advancing action for shifting the stitch finger with respect to the field of stitch formation to a different predetermined position respectively for intervals of the same number of stitch forming cycles.

7. In a sewing machine in combination with stitch forming elements, work feeding mechanism for advancing the work at intervals wherein respectively the number of stitch forming cycles varies, and means for effecting a different tension upon the thread respectively for intervals of the same number of stitch-forming cycles.

8. In a sewing machine, in combination with stitch forming elements, work feeding mechanism for advancing the work at intervals wherein respectively the number of stitch-forming cycles varies, a stitch finger, means for shifting the stitch finger to a different predetermined position respectively for intervals of the same number of stitch forming cycles, and means for effecting a different tension upon the thread respectively for intervals of the same number of stitch forming cycles.

9. In a sewing machine, in combination with stitch forming elements, a work plate, a feed dog, a rotary shaft, mechanism driven by the shaft for reciprocating the feed dog, a pinion rigid with the shaft, a gear in mesh with the pinion, a cam associated with the gear, a stitch finger slidably supported by the work plate, and means including a rock shaft interposed between the cam and stitch finger whereby the latter may be moved to alter the character of the stitching.

10. In a sewing machine in combination with stitch forming elements, a work plate, a stitch finger movably supported by the work plate, a thread tensioning device, a lever associated with the thread tensioning device, and movable to vary the tension effected thereby, means for moving the stitch finger into different positions with respect to the field of stitch formation, means for moving the lever associated with the tensioning device to differently tension the thread for each position of the stitch finger and a thread controlling element movable with said lever adapted to engage the thread between the tensioning device and the needle.

11. In a crotchet machine in combination with stitch forming elements including a supplemental thread carrier, a needle actuating lever fulcrumed upon the machine frame, a thread tensioning device carried by the lever near its fulcrum, thread guides on the machine frame and a thread engaging element carried by the lever and movable thereby between the thread guides, the

movement imparted to the tension device and thread engaging element serving to control the take-up and pull-off of the supplemental thread.

- 5 12. In a shell-stitch machine in combination a work plate, a stitch finger slidably supported by the work plate, stitch forming elements including a reciprocating needle, and a crotchet hook, the latter being operable in a path extending across the needle path above and below the work plate and around the stitch finger, means for feeding the work at intervals of different duration and means for effecting a change in the position of the stitch finger for different intervals.
- 10 13. In a shell stitch machine in combina-

tion, a work plate, a stitch finger slidably supported by the work plate, stitch forming elements including a reciprocating needle 20 and a crochet hook, the latter being operable in a path extending across the needle path above and below the work plate and around edge of the stitch finger, means for feeding the work at intervals of different 25 duration, means for effecting a change in the position of the stitch finger for different intervals and means for effecting a change in the tension upon the thread for different intervals.
